PROCESS AND APPARATUS FOR CONVERTING HYDROCARBON OILS

Claude W. Watson, Port Arthur, Tex., assignor to The Texas Company, New York, N. Y., a corporation of Delaware

Application July 19, 1928. Serial No. 293,869

12 Claims. (Cl. 196—49)

This invention relates to cracking processes and contemplates the removal, at the proper stage of the treatment or conversion, of the carbon and coke and elements tending to form the same when charging a heavy oil of the nature of topped crude oil or fuel oil to a cracking process.

The invention contemplates heating the entire charge of heavy oil to an elevated temperature while under several atmospheres of pressure and separating out the carbon, residue and objectionable heavier compounds from the oil undergoing treatment, and ridding the system of such components by removing them from a separating zone while delivering an overhead vapor comparatively free of carbon and coke to a reaction or vapor conversion zone for further treatment.

While there is illustrated and described a preferred embodiment of the invention in which the apparatus is adapted to carry out a liquid phase cracking process it will be understood that the oil undergoing treatment is in vapor form when leaving the separating zone and may therefore be further treated in the vapor phase, as for example in a so called converter.

In the normal operation of the process topped crude or other heavy petroleum fractions may be charged to a heating coil of restricted area wherein a suitable superatmospheric pressure, which may be 100 pounds per square inch or more, may be maintained. The said charge preferably may be commingled with a reflux condensate at some intermediary point in the said heating coil and be highly heated in transit therethrough. Upon leaving the heating coil the highly heated oil which may have a temperature of the order of 850° F., is conducted to the first stage of separation and delivered into an enlarged primary or high pressure chamber upon a hood or other means which may act as a spreader for the entering liquid while acting as an umbrella under which evolved vapor may gather and be withdrawn. A pressure within the said chamber is preferably maintained substantially equal to that existent in the heating coil and I refer to this part of the separating zone as the high pressure stage. The highly heated oil entering is distributed upon a spreader within the top of the said enlarged chamber and flows down upon the outside of the spreader skirt or hood in a film and evolves and separates into a vapor and a liquid fraction. The liquid fraction flowing down and depositing itself within the bottom of the chamber is continuously and regulatively withdrawn.

The hot oil withdrawn from the first stage of

separation is conducted to the second stage of separation and delivered into a second enlarged chamber of the same general description as the first described. In the second chamber the pressure is preferably carried very much lower than the pressure in the first chamber and I refer to the second chamber as the low pressure stage. At times however in this stage I may wish to approach the pressure carried in the first chamber. The hot liquid entering the said second chamber evolves and separates into a vapor fraction and a liquid fraction. The liquid depositing itself within the bottom of the said second chamber may be continuously and regulatively removed therefrom and discharged from the system. This liquid may ordinarily include carbon, residue and objectionable compounds which tend to form coke and generally hinder the continuous successful operation of the equipment. As proper fractionation is often difficult to accomplish I provide for a certain amount of agitation of the liquid, either violent or gentle, in this second chamber.

It is obvious that more than two chambers in more than two stages of separation may be employed operating at any desired pressure. In the particular example of the invention under discussion two chambers in two stages seem sufficient, however I may employ more in treating different oils.

The vapor evolved in the first chamber is withdrawn from a sheltered area so as to exclude substantially all of the liquid particles and the said vapor, being of considerable volume, is delivered at high velocity through compression means, which may be of the jet compressor type, and in passage therethrough may pick up or entrain the vapor from the second chamber which is gathered from the second chamber in a sheltered area, so that it too is free from substantially all liquid particles. Both the vapor fraction from the first chamber and from the second chamber in the separating zone are thereby commingled and the relatively clean vaporous admixture is delivered into the reaction zone or converter which may also be maintained under superatmospheric pressure. Naturally the pressure in the reaction zone or converter would be lower than the pressure in the first chamber of the separating zone but ordinarily very much higher than the pressure in the second chamber. By relatively clean vapor I mean a vapor which when condensed would become a liquid substantially free of free carbon and coke.

With this and other objects in view the inven-

tion is more fully described in the following specification and defined in the claims.

The features of this invention are illustrated in the accompanying drawing in which an apparatus 5 suitable for carrying on the process is shown in diagrammatic elevation with certain parts in sectional elevation, although it will be understood that any other apparatus of suitable type may be adapted for practicing the said invention.

10 Referring to the drawing:

Heavy oil to undergo treatment may be passed in heat exchange through closed coil 1 in reflux exchanger 64 and entering the system through pipe 2 may be passed through an economizer bank 15 or section 3 and forced into the heating coil or preheater 4 of suitable design to withstand high pressure and temperature. There is provided a line 5 for the introduction of reflux condensate into lower portion of the heating coil 4.

20 The highly heated oil upon emerging from the heating coil 4 is conducted through pipe 10 provided with drain line 11 to the enlarged heat insulated chamber 15.

The highly heated oil emerges from pipe 10 25 through a suitable distributing nozzle 12 situated near the top and within the chamber 15, and is delivered upon spreading means 13, being preferably constructed conically and having a vertical skirt 14. Such fraction of the oil as remains in liquid 30 form deposits itself in the bottom of the chamber 15 and is regulatively withdrawn therefrom by means of the pipe 16 and the interposed valve 17, which may be controlled by the rise and fall of the float 18, buoyed up by the level of liquid within 35 the chamber 15. Ordinarily I may carry a high pressure in the chamber 15.

The hot oil emerging from pipe 16 is conducted through the distributing nozzle 25 situated within the top of the heat insulated chamber 20 and is 40 delivered upon spreading means 26, being preferably constructed conically and having a vertical skirt 27. Ordinarily I may carry a much lower pressure in the chamber 20 than in the chamber 15.

45 Such fraction of the oil as remains liquid in chamber 20 deposits itself within the bottom of the said chamber and is regulatively withdrawn from the system by means of the pipe 21 and the interposed valve 22, which may be controlled by the rise and fall of the float 23 buoyed up by the level of liquid within the chamber 20.

Suitable stirring or agitating means 24 is provided within the bottom of chamber 20, driven at any desired speed by means not shown.

50 That fraction of the highly heated oil vaporized in the chamber 15 is gathered from beneath the spreader 13 and conducted from the chamber 15 by means of the pipe 30.

55 That fraction of the hot oil vaporized in the chamber 20 is gathered from beneath the spreader 26 and conducted from the chamber 20 by means of the pipe 31.

The vapor leaving the chamber 15 (in which the higher pressure is maintained) through pipe 60 30 at high velocity encounters the vapor leaving chamber 20, through pipe 31 at lower velocity, in compression means 35 which may be of the jet compressor type.

65 It is to be understood that in some cases it likely will be necessary to employ other means for compressing the vapors and forcing them on through the other stages of the process.

70 Valve 32 is provided in line 30 and valve 33 is provided in line 31 for regulating the pressures 75 within chambers 15 and 20 respectively and the

flow of fluid therefrom. The admixture of vapors from the chambers 15 and 20 is conducted through pipe 40 to reaction chambers 45 and 46 maintained under a pressure somewhat reduced from that in chamber 15.

80 The vaporous products entering the reaction chambers 45 and 46 near the bottom through pipes 47 and 49 having valves 48 and 50 are subjected inside the reaction chamber to a pressure and temperature slightly reduced from that existing in the chamber 15, but sufficient to be considered cracking conditions.

85 It is to be understood that I may either insulate the reaction chambers 45 and 46 or I may provide heating means to maintain a desired temperature.

90 During the period of reaction within vessels 45 and 46 there is formed a liquid condensate which upon depositing in the lower portion of the vessels 45 and 46 may be withdrawn by means of the pipes 55 and 57 and the valves 56 and 58, while there is evolved an overhead vapor fraction which may emerge through the pipe 60. The vessels 95 45 and 46 are provided with open communicating means 51 and 52 of suitable size.

100 The overhead vapor conducted through pipe 60 may be delivered to dephlegmating means 61 and a liquid condensate which may be used for refluxing may be withdrawn from the bottom of dephlegmating means 61 by means of the pipe 62, 105 while the vapor may be withdrawn from overhead through pipe 63 and conducted through reflux exchanger 64 to be delivered to condensing means 66 by means of pipe 65. The desired distillate may be withdrawn from condenser 66 by means of 110 pipe 67, conducted through metering means 68 and delivered to storage.

115 Obviously many modifications and variations of the invention, as hereinbefore set forth, may be made without departing from the spirit and scope thereof, and therefore, only such limitations should be imposed as are indicated in the appended claims.

I claim:

120 1. In the conversion of higher boiling hydrocarbons the process of highly heating oil under superatmospheric pressure to cracking temperature, delivering the highly heated oil into the high pressure stage of a separating zone having a high pressure stage and a low pressure stage, flashing off in the said high pressure stage the more volatile products to form a vapor fraction and a hot liquid fraction, delivering the said hot liquid fraction to the said low pressure stage, flashing off in the low pressure stage the more volatile products of the said hot liquid fraction to form a vapor fraction and a liquid fraction, delivering the said vapor fraction at high velocity from the high pressure stage as formed through a restricted orifice to thereby entrain the said vapor fraction from the low pressure stage as formed and therefrom delivering the total admixture to a conversion zone.

125 2. In the conversion of higher boiling hydrocarbons the process of highly heating oil under superatmospheric pressure to cracking temperature, delivering the highly heated oil into the high pressure stage of a separating zone having a high pressure stage and a low pressure stage, flashing off in the said high pressure stage the more volatile products to form a vapor fraction and a hot liquid fraction, delivering the said hot liquid fraction to the said low pressure stage, flashing off in the low pressure stage the more volatile products of the said hot liquid fraction to form a 130 vapor fraction at high velocity from the high pressure stage as formed through a restricted orifice to thereby entrain the said vapor fraction from the low pressure stage as formed and therefrom delivering the total admixture to a conversion zone.

135 3. In the conversion of higher boiling hydrocarbons the process of highly heating oil under superatmospheric pressure to cracking temperature, delivering the highly heated oil into the high pressure stage of a separating zone having a high pressure stage and a low pressure stage, flashing off in the said high pressure stage the more volatile products to form a vapor fraction and a hot liquid fraction, delivering the said hot liquid fraction to the said low pressure stage, flashing off in the low pressure stage the more volatile products of the said hot liquid fraction to form a 140 vapor fraction at high velocity from the high pressure stage as formed through a restricted orifice to thereby entrain the said vapor fraction from the low pressure stage as formed and therefrom delivering the total admixture to a conversion zone.

145 4. In the conversion of higher boiling hydrocarbons the process of highly heating oil under superatmospheric pressure to cracking temperature, delivering the highly heated oil into the high pressure stage of a separating zone having a high pressure stage and a low pressure stage, flashing off in the said high pressure stage the more volatile products to form a vapor fraction and a hot liquid fraction, delivering the said hot liquid fraction to the said low pressure stage, flashing off in the low pressure stage the more volatile products of the said hot liquid fraction to form a 150 vapor fraction at high velocity from the high pressure stage as formed through a restricted orifice to thereby entrain the said vapor fraction from the low pressure stage as formed and therefrom delivering the total admixture to a conversion zone.

- vapor fraction and a liquid fraction, delivering the said vapor fraction at high velocity from the high pressure stage as formed through a restricted orifice to thereby entrain the said vapor fraction 5 from the low pressure stage as formed, delivering the total admixture to a conversion zone, evolving therein a liquid condensate and an overhead vapor, conducting the said overhead vapor to dephlegmating means, forming therein an overhead vapor and a reflux condensate and conducting the said overhead vapor to condensing means to form a desired distillate. 10
3. In the conversion of higher boiling hydrocarbons the process of highly heating oil under superatmospheric pressure to cracking temperature, delivering the highly heated oil into the high pressure stage of a separating zone having a high pressure stage and a low pressure stage, flashing off in the said high pressure stage the more volatile products to form a vapor fraction and a hot liquid fraction, delivering the said hot liquid fraction to the said low pressure stage, flashing off in the low pressure stage the more volatile products of the said hot liquid fraction 15 to form a vapor fraction and a liquid fraction, delivering the said vapor fraction at high velocity from the high pressure stage as formed through a restricted orifice to thereby entrain the said vapor fraction from the low pressure stage as formed, delivering the total admixture to a conversion zone, evolving therein a liquid condensate and an overhead vapor, conducting the said overhead vapor to dephlegmating means, forming therein an overhead vapor and 20 a reflux condensate and conducting the said overhead vapor to condensing means to form a desired distillate while returning the said reflux condensate to a heating zone with the initial charge and highly heating the mixture. 25
4. In the conversion of higher boiling hydrocarbons the process of highly heating oil under superatmospheric pressure, to cracking temperature, delivering the highly heated oil into the high pressure stage of a separating zone having a high pressure stage and a low pressure stage, flashing off in the said high pressure stage the more volatile products to form a vapor fraction and a hot liquid fraction, delivering the said hot liquid fraction to the said low pressure stage, flashing off in the low pressure stage the more volatile products of the said hot liquid fraction 30 to form a vapor fraction and a liquid fraction, delivering at high velocity the said vapor fraction from the high pressure stage as formed through a restricted orifice to thereby entrain the said vapor fraction from the low pressure stage as formed and delivering the total admixture to a reaction zone operating under a pressure higher than the low pressure stage of separation. 35
5. In a cracking operation where the oil undergoing cracking is passed successively through heating zones, a separating zone having two different pressure stages, and a conversion zone; the process of evolving vapors in the two different pressure stages of the said separating zone, employing kinetic energy of the evolved vapor escaping from the high pressure stage to entrain the vapor evolved in the low pressure stage and to deliver the admixture to the conversion zone operating under a pressure higher than the low pressure stage of separation. 40
6. In a cracking operation where the oil undergoing cracking is passed successively through heating zones, a separating zone having high and low pressure stages, and a reaction zone; the process of delivering highly heated oil from the heating zones to the high pressure stage of the separating zone, vaporizing therein the more volatile components, delivering a hot liquid fraction at cracking temperature from the high pressure stage of the separating zone to the low pressure stage of the separating zone, vaporizing in the said low pressure stage the more volatile components of the said hot liquid fraction delivered thereto, conducting the vapor evolved in both stages to jet compressing means, therein intermingling the two vapors and utilizing the energy of the higher pressure vapor for injecting the total admixture into the reaction zone under pressure above that maintained in the low pressure stage. 45
7. In a cracking operation where the oil undergoing cracking is passed successively through heating zones, a separating zone having different pressure stages, and a reaction zone; the process of delivering highly heated oil at a cracking temperature from the heating zone into the high pressure separating stage, therein forming an overhead vapor fraction while depositing a liquid fraction, continuously conducting the said liquid fraction to another stage of separation maintained under reduced pressure, therein forming an overhead vapor fraction and depositing a liquid fraction, delivering the vapor fraction from the said high pressure stage at high velocity 50 through a restricted orifice to thereby entrain the vapor fraction from the said reduced pressure stage and delivering the vaporous admixture into the reaction zone under pressure above that maintained in the low pressure stage while withdrawing the liquid fraction from the said reduced pressure stage of separation. 55
8. In a cracking operation where the oil undergoing cracking is passed successively through heating zones, a separating zone having several stages operating under different pressures, and a reaction zone; the process of highly heating the oil, subjecting the highly heated oil to the different pressure stages of separation to thereby evolve relatively clean vapor fractions, utilizing the energy of the high pressure vapor to recom- 60 press the low pressure vapor, and delivering a combined relatively clean vapor fraction to the reaction zone under pressure above that maintained in the low pressure stage but below that maintained in the high pressure stage while discharging a carbon and coke containing liquid fraction from the separating zone. 65
9. In an apparatus for the conversion of hydrocarbon oils the combination of a heating coil, a plurality of separators serially connected, means for passing oil successively through the heating coil and said separators, means for maintaining a differential pressure on said separators, a reaction chamber, vapor lines for removing vapors from said separators, jet compressor mixing means for commingling said vapors and means for passing commingled vapors to the reaction chamber. 70
10. In an apparatus for conversion of hydrocarbon oils the combination of a heating coil, a primary separator, means for passing oil from the heating coil to said primary separator, a reaction chamber, a vapor line for conducting vapors from said separator to the reaction chamber, a secondary separator maintained under reduced superatmospheric pressure lower than that of said reaction chamber, means for passing unvaporized oil from the primary to said secondary separator, compressing means for with- 75

drawing vapors from said secondary separator and for compressing said vapors and forcing them into the said reaction chamber.

11. The process of treating hydrocarbon oil which comprises heating said oil to a cracking temperature under superatmospheric pressure, separating lighter products in vapor form from unvaporized residue, expanding said residue by reducing the pressure thereon, with resulting evolution of additional vapors, reducing the pressure on the vapors of said lighter products to a lower value, but one in excess of the pressure on the expanded residue, utilizing the kinetic energy of the expanding vapors of said lighter products to entrain said additional vapors and increase the pressure thereon, and fractionating resultant mixed vapors under said pressure last mentioned, to produce a desired product.

12. The process of effecting the conversion of hydrocarbon oil to oil of lower boiling point which comprises heating a confined flowing stream of

such oil to a cracking temperature under a high superatmospheric pressure, discharging the heated oil stream into an enlarged reaction zone wherein it undergoes further cracking under said pressure and wherein separation of vapors and liquid takes place, passing vaporous products from said reaction zone to a fractionating zone maintained under a materially lower pressure, separately withdrawing residual liquid from said reaction zone, passing it to a second reaction zone wherein it undergoes further cracking, evolving vapors from said residual liquid at a pressure below that obtaining in said fractionating zone, and ejecting said evolved vapors into said fractionating zone by the energy of the vaporous products flowing thereto under high pressure from said first mentioned reaction zone, and cooling the vaporous products in said fractionating zone to recover the desired lower boiling oil therefrom.
